The ornamental design for a pull-tab of slider for slide fastener, as shown and described.

(30) **Foreign Application Priority Data**

DESCRIPTION

Mar. 15, 2011 (JP) D2011-005903

FIG. 1 is a perspective view of the bottom, front and right side of a pull-tab of slider for slide fastener showing my (our) new design;

(51) **LOC (9) Cl.** **02-07**

FIG. 2 is a front view thereof;

(52) **U.S. Cl.** **D11/221**

FIG. 3 is a rear view thereof;

(58) **Field of Classification Search** D11/200,

FIG. 4 is a top plan view thereof;

D11/201, 221; 24/381-383, 385-387, 414-417,
24/421-422, 427-431, 433; 2/265

FIG. 5 is a bottom view thereof;

See application file for complete search history.

FIG. 6 is a right side view thereof; and,

(56) **References Cited**

FIG. 7 is a reference view of usage.

The portions shown in broken lines are for illustrative purpose only and form no part of the claimed design.
